UNITED STATES PATENT OFFICE.

WILLIAM J. HIGGINS AND CHRISTOPHER J. SHERIDAN, OF BUFFALO, NEW YORK.

ELECTRIC SIGNALING SYSTEM FOR RAILWAYS.

1,245,589.

Specification of Letters Patent.

Patented Nov. 6, 1917.

Application filed July 29, 1908. Serial No. 445,875.

To all whom it may concern:

Be it known that we, WILLIAM J. HIGGINS and CHRISTOPHER J. SHERIDAN, citizens of the United States, and residents of Buffalo, 5 in the county of Erie and State of New York, have invented certain new and useful Improvements in Electric Signaling Systems for Railways, of which the following is a specification.

10 Our invention relates to railway signaling systems, wherein a cautionary or danger signal, or both, is given by means of semaphore arms or lights and particularly relates to that type of railway signals known 15 as "block systems" and in which the apparatus is automatically regulated in its action by electricity.

The idea of our invention comprehends utilization of a normally closed track circuit 20 to control the operation of a signaling circuit to indicate a clear block and the elimination of the control of the track circuit to energize a signaling circuit to positively operate danger or cautionary signals in the 25 block in the rear of the train.

Our invention further comprehends the employment of suitable electrically-operated means for imparting a waving motion to the semaphores or to lights located thereon, or for 30 producing intermittent signals by utilizing the waving of the semaphores as a shutter before stationary lights and our present invention further comprehends the employment of a metallic circuit as adapted for 35 use in electric railways.

In the drawings forming part of this specification:

Figure 1 is a diagram of the preferred arrangement of wiring and the preferred location of the signals relative to the various 40 blocks;

Fig. 2 is a fragmentary front view of a semaphore embodying our idea of means for intermittent or flash-light signals and a practical means for operating the same;

Fig. 3 is a side view of the construction shown in Fig. 2;

Fig. 4 is a fragmentary view of our invention as adapted to the semaphore arms to 50 produce a waving signal; and

Fig. 5 is a side or edge view of a convenient means for attaching the signal-light to the end of the semaphore arm.

In the performance of our invention, when 55 a high voltage is used for a long distance transmission, we prefer to employ what are

termed step-down transformers in each block and we also employ two series of split transformers, one being set on each side of the track, one series being in the signaling circuit of the cautionary-signal and the other in the signaling circuit of the danger-signal, and each adapted to energize secondary coils carried by the train to actuate suitable signals located therein.

In the drawings, we have illustrated our invention as adapted to a double-track system wherein A designates the two rails of the track, which are divided into four blocks or sections by proper insulation at the rail-joints *a* and opposite rails of each block are respectively connected with batteries B preferably located between the rails. The rails of each block form a part of the metallic circuit including relays R' R'' R''' of ordinary construction. The terminals of each relay are connected with the rails of each block of the track and normally the two rails of the track, the battery and the relays are in closed circuit acting to hold the armature 75 or switch-arm S against a stop *x* and against the force of a controlling-spring 2. The stop *x* is connected by means of a suitable conductor 4' to a light L''' located on the signal-post and comprises a block-signal indicating 80 a clear or safe block. The circuit of the clear block-signal includes the transformer E, conductors 4' and 4. A stop *x'*, suitably located in relation to the armature or switch-arm S, is connected by suitable conductors 85 to a danger-signal operating in the block the train occupies and with a cautionary-signal operating in the block next preceding.

Each danger-signaling circuit comprises the transformer E, the armature switch-arm S, 90 the stop *x'* and a conductor 5 leading to the induction-motor M', located on the signal-post and adapted to operate the danger semaphore D', the danger-signal light L, and is completed through a conductor 4 to 100 the transformer. This circuit includes a track-coil D, located, preferably, on the right side of the track, which is utilized to operate danger-signals carried by the passing train.

Each cautionary signaling circuit comprises the transformer E, the armature switch-arm S, conductors 3, 3', and induction-motor M, located on the signal-post and adapted to operate the cautionary semaphore C', a cautionary-signal lamp L' and return 105 to the transformer by means of conductors 6', 4. This cautionary circuit includes track-

coils C preferably located on the left side of the track, which is utilized to operate cautionary-signals carried by the passing train. The feed-line F connects with the trans-formers E in a suitable manner.

For convenience, we have indicated the signals as set and appearing in the blocks, presuming the train to be located in block III at the point Z and traveling in the direction of the arrow and we have indicated for each block the signals and the signal-lights set and appearing therein. Block IV is clear and a white light L''' indicates safety and the semaphores are at rest; block III, train block, a red light L indicating danger and danger semaphore in operation; and block II a white light L''' indicating safety and a green light L' indicating caution and a cautionary semaphore in operation.

The electro-mechanical part of our invention is particularly designed to produce an effective method of signal-lights by night and comprises for each signal-post induction electric motors M M', which operate semaphores C' D', through spur-gears M'' M''' and pitman D'' to cause a waving or up and down motion to the semaphore arms and at the same time cause an intermittent or flashlight as the arms move in front of the signal-light, which, in case of danger, would show red, as L, or, in case of caution, green, as L'. The lights L, L' and L''' are provided with powerful reflectors L^{IV} and we have found it desirable to employ a frame L'', provided with red or green glass shields rather than to use a red or green light bulb.

For the purpose of signaling more in accord with the trainmen's usage, we have placed a light L^V in the semaphore-arm itself as far from its axis of motion as possible and have provided this light with a strong reflector L^{IV} and with a proper signal colored shield so that, when the semaphore operates up and down, as controlled by its motor and operative mechanism, this light will move up and down to accentuate the signal and more effectually detach it from the darkness, as such a moving signal is familiar to trainmen.

To particularly describe the operation of our system, with reference to Fig. 1, as we have said, we assume the train to be in block III, traveling in the direction of the arrow. It will, therefore, be apparent that the track-circuit is short-circuited through the axle and wheels of the car, cutting out the resistance of the relay R'' and allowing the switch-arm S to be drawn by the spring 2 against the stop w', thereby completing the circuit F through the secondary of the trans-former E and conductor f, to the danger-conductor 5 and the danger-semaphore D' and danger-light L located in the train-block II. At the same time, it will be perceived that the shunting of this current breaks the

safety-light circuit in block II and there-upon, the safety-light L''' goes out and the only light remaining in the block will be the red or danger light. At the same time, through a branch 3 of the danger-conductor 5, the current travels to the second preceding block I in rear of the train-block III and actuates the cautionary-semaphore C' and the cautionary-light L'. It will, therefore, be perceived that the block in which the train is located, or, as we term it, the train-block, is guarded at its entrance by means of a red light or danger-signal, while the block in rear of the train-block is guarded at its entrance by a white light or cautionary-signal indicating that the second block ahead is occupied by a train. The block in advance of the train-block and indicated as block IV in the drawing is guarded by a white light.

Having described our invention, what we claim is:

1. In a block signaling system, in combination with a plurality of train-blocks; a track-circuit for each train-block; a plurality of normally opened and closed signal-circuits in each block and including a plurality of signals of different character arranged to operate with reference to said block; a main feed-line common to all the blocks and signal circuits; a relay located in each track-circuit and normally controlling the signals of the normally opened and closed signal-circuits of that block; and means whereby, when a train is in one train-block, signals in said block and a preceding block differing in character may be simultaneously operated.

2. In a block signaling system, the combination with a plurality of train-blocks; a track-circuit in each block; a signal-circuit corresponding to each block, a branch signal circuit extending into successive blocks; signals of different character in said branch signal-circuit; a relay in each track-circuit; a switch corresponding to each block normally controlled in a predetermined manner by the relay; and means co-operating with the relay whereby the latter will be caused to change its control of the switch so as to energize each branch of signal-circuit and display different signals in successive blocks.

3. In a block signaling system, the combination with a plurality of train-blocks; a normally-closed track circuit arranged in each block; a branched signal-circuit corresponding to each block and extending into successive blocks and having one branch normally closed to control a signal; a plurality of signals of different character in each signal-circuit; a relay in each track-circuit; a switch corresponding to each block normally controlled by the relay to close said normally closed branch; and means carried by the moving train for causing the track-

circuit to operate the relay to open said normally closed branch of the signal-circuit and close another branch of said signal circuit and control the operation of the various signals in said circuit.

4. In a block signaling system, the combination with a plurality of train-blocks; a normally closed track-circuit for each of said train blocks; a branched signal-circuit

10 corresponding to each block and extending into successive blocks and one branch of which is normally closed and contains a safety signal, and other branches of which are normally open and contain danger and

15 cautionary signals, respectively; a relay in each track-circuit; a switch for each relay operated by the latter to control the said branches of the corresponding signal circuit; and means carried by the moving train to

20 short-circuit the track-circuits and close the normally open branches of the signal-circuits so as to operate the said danger and cautionary signals contained therein.

5. In a block signaling system, the combination with a plurality of train-blocks; a track-circuit in each of said blocks; a signal-circuit corresponding to each block comprising normally opened and closed branches, one of which extends into successive blocks; 30 signals controlled by said branch circuits; an electro-magnetic device located in each track-circuit; means coöperating with said device arranged to control said branch signal-circuits for producing different signals.

35 6. In a block signaling system, the combination with a plurality of train-blocks; a track-circuit in each of said blocks; a signal-circuit corresponding to each block comprising a normally opened and closed branch; 40 said opened branch having a branch therefrom extending into another block; an electro-magnetic device located in each track-circuit; means coöperating with said devices adapted to control the operation of the signaling-circuits; and means in the branches of the signal-circuit for producing different signals.

7. In a block signaling system, the combination with a plurality of train-blocks; a 50 track-circuit in each of said blocks; a signal-circuit corresponding to each block and having a normally closed branch and also having normally opened branches extending into successive blocks, each of the latter 55 branches having therein signals of different type but of the same significance; an electro-magnetic device located in each track-circuit; and means coöperating with said device adapted to open and close said signal 60 circuits according to the conditions of the track-circuit.

8. In a block signaling system, the combination with a plurality of train-blocks; a closed track-circuit for each block; a 65 branched signal-circuit corresponding to

each block and having one branch normally closed and controlling a signal therein; a relay in each track-circuit; a switch co-operating with the relay and normally controlled thereby to close said branch; and 70 means forming part of the moving train for influencing the track-circuits to close another branch of the signaling-circuits and produce a signal therein.

9. In a block signaling system, the combination with a track-circuit; a signal-circuit having a plurality of branches one of which is normally closed; an electromagnetic device located in the track-circuit and having means adapted to control the signal-circuit; 75 a post having a semaphore arm; a motor located in a branch of the signal-circuit so as to be actuated under control of the electromagnetic device; means connecting said motor and said semaphore arm; and a light 80 located on one of said elements and arranged to produce signals as the semaphore arm is actuated.

10. In a block signaling system, the combination with a plurality of train-blocks; a 90 normally-closed track-circuit for each of said blocks; a branched signal-circuit corresponding to each of said blocks and having one of its branches normally closed and another branch normally opened; an electromagnetic device in each track-circuit; means coöperating with said device to open and close the branches of the signal circuit; a motor in the normally opened branch of the 95 said signaling-circuits so as to be actuated under control of the electro-magnetic device; and suitable means operated by said motor for producing waving signals. 100

11. In a block signaling system, the combination with a normally-closed track-circuit; a branched signal-circuit corresponding to each of said blocks and having one branch normally closed and controlling signals therein; a relay in the track-circuit; a switch mechanism coöperating with the 110 relay to control the signal-circuit; a motor located in another branch of the signal-circuit; so as to be actuated under control of the electro-magnetic device; and suitable means operated by the said motor for producing waving signals in the signaling circuit. 115

12. In a block signaling system, the combination with a plurality of train-blocks; a normally-closed track-circuit for each of 120 said blocks; a branched signal-circuit for each block having one branch normally closed and controlling the safety signal thereof; a relay in each track-circuit; comprising normally closed and normally opened 125 branch circuits for controlling signals; a switch mechanism coöperating with the relay for alternatively closing the safety branch of the signal-circuit and for opening the danger or cautionary branch of said circuit; 130

- and signaling means located in the danger or cautionary branch of the signal-circuit, including devices for producing predetermined signals.
5. 13. In a block signaling system, in combination, a track-circuit; a signal-circuit comprising normally closed and normally opened branch circuits for controlling signals; a relay in the track-circuit; a switch 10 coöperating with the relay for opening and closing said branch signal-circuits; and means on a train to short-circuit the track-circuit for operating said switch so as to operate the signals in said signal-circuit.
15. 14. In a block signaling system, in combination with a plurality of train blocks; of a track-circuit for each train block; a plurality of signal-circuits in each block; a main feed line for all the signal-circuits for 20 each block; a relay in each track-circuit; a shiftable means in each block extending from said feed line and influenced by said relay to alternately make and break certain signal-circuits of each block according to the 25 condition of the track-circuit.
15. In a block signaling system, in combination with a plurality of train blocks; of a track-circuit for each train block; a plurality of signal-circuits in each block; a 30 main feed line for all the signal-circuits for each block; means in said feed line for supplying each signal-circuit of each block with a supply of current; a relay in each track-circuit; and shiftable means for each block 35 extending from said means in the feed line and influenced by said relay to alternately make and break certain circuits of each block according to the condition of the track-circuit.
40. 16. In a block signaling system, in combination with a plurality of train blocks; of a track-circuit for each train block; a plurality of signal-circuits in each block; a main feed line for all the signal-circuits for 45 each block; signals in said signal-circuits; a plurality of transformers in said feed line coöperating respectively with said train block; a relay in each track-circuit; shiftable means connected with the secondary of
- each transformer and under the influence of 50 said relay to alternately open and close different signal-circuits in its respective block according to the conditions of the track-circuit thereof.
17. In a block signaling system, in combination with a plurality of train blocks, of a track-circuit for each train block; a plurality of signal-circuits corresponding to each block and comprising a plurality of 55 normally opened and normally closed 60 branch circuits, one of said branch circuits extending into successive blocks; signals in each branch circuit and controlled thereby; a feed line for all the signal-circuits of each 65 block; and means in said feed line for supplying each branch of the signal-circuits of each block with a supply of current; a relay in each track-circuit; a shiftable means in each block extending from said means in the feed line and influenced by said relay to 70 alternately open and close the branch circuits of its respective block according to the condition of the track-circuit thereof.
18. In a block signaling system, the combination with a plurality of train blocks; a 75 track-circuit in each block having a relay therein; a branched signal-circuit for each block, each branch having a signal of predetermined character; a main feed line having a plurality of transformers, one for each 80 block, and including a primary and a secondary; a switching device for each block coöperating with the relay thereof and normally controlled thereby to close one of the signal branches and operate the signal 85 thereof, said device being in the circuit including the secondary of the transformer of said block; and means for actuating said switching device to shift the feed line current to another signal branch so as to 90 actuate the signal thereof.
